UNITED STATES PATENT OFFICE.

JOSEPH A. SCHMITZ, OF CHICAGO, AND ADYN E. SCHUYLER, OF EVANSTON, ILLINOIS.

GRAIN DOOR FOR FREIGHT CARS.

Application filed July 13, 1923. Serial No. 651,236.

To all whom it may concern:

Be it known that we, JOSEPH A. SCHMITZ and ADYN E. SCHUYLER, citizens of the United States, residing, respectively, at

5 Chicago, in the county of Cook and State of Illinois, and at Evanston, in the county of Cook and State of Illinois, have invented certain new and useful Improvements in Grain Doors for Freight Cars, of which the following is a specification.

Our invention relates to a device which we have invented for forming a closure for the door opening of box cars and is particularly adapted for use in shipping grain.

15 It is now the practice to employ for this purpose standard door sections made according to various specifications adopted by the different railroad companies, these doors being supplied to shippers by the railroads.

20 The sections are uniformly seven feet in length and twenty inches in width, and are frequently constructed of two thicknesses of lumber making broken joints, the boards on one side being shorter than the other to

25 provide for a cross-piece of the same thickness as the other boards at each end, these cross-pieces being designed to be placed facing the inside of the car when the section is in use, as in the typical door illustrated

30 in the drawing. As ordinarily used, these door sections are simply nailed across the door opening, one above another, from three to five sections being employed, sometimes three sections being used, as illustrated, and often four, and less frequently five.

35 In unloading cars thus loaded with grain, it is the common practice to remove the top door first; then the next lower, etc., in succession, as the grain level is lowered in the car. As the grain is compacted by the jarring to which the car is subjected in trans-

40 portation, particularly the lower portion of the grain, it is by no means an easy matter to remove the doors. This is done, when a car has been properly loaded, by forcing the ends of the door inwardly by heavy pointed iron bars against the pressure of the grain to unseat the nails, and then forcing the doors upwardly. The second door

45 from the bottom is usually especially hard to dislodge. In some cases, where the shipper has ignorantly applied a reinforcement inside the closure connecting two doors it is sometimes necessary to chop an opening 50 in the bottom door to let the grain flow out at that point to the unloading hoppers. In

any case the doors are liable to be subjected to very rough treatment in removing them, and are frequently so broken or damaged as to be no longer serviceable. 60

Since the door sections are removed one by one, the flow of the grain proceeds by stages, and as a number of cars, frequently five or six, are simultaneously unloaded at one long platform, an interruption of the 65 unloading operation, due, it may be to improper closure of one of the cars, results in delay to all the others.

It is the object of our invention to facilitate the unloading of grain and prevent 70 damage to standard grain door sections, such as those above mentioned, by providing a destructible and replaceable bottom closure member and associated securing and bracing means adapted to be used in connection with the standard door sections mentioned, so that an opening can be readily made along the floor line of the car, and the door sections taken down as soon as the pressure is relieved and while the car is being emptied. With this object in view we have devised and invented the car door closure hereinafter more fully described, and our invention resides in the construction 75 and arrangement of the cooperating parts and members of such closure, the essential elements thereof being more fully pointed out in the appended claims.

80 In the accompanying drawings we have illustrated our invention in a preferred 85 form, Figure 1 being a side elevation of a portion of a box car showing our closure applied thereto; Fig. 2 a vertical section on the line 2—2 of Fig. 1; Fig. 3 a vertical section on a somewhat larger scale, showing the manner in which the grain opening is made at the bottom of the closure; Figs. 4 and 5 are vertical and horizontal sections 90 respectively showing the means for securing the upper end of the wrench bar; Fig. 6 a fragmentary horizontal section adjacent the lower end of the wrench bar; Fig. 7 a perspective view of an alternative securing means; and Fig. 8 a fragmentary vertical section adjacent the lower end of the wrench 95 bar, showing the use of a cleat for restraining outward movement of the bar.

100 The same reference characters indicate the same parts in all the figures of the drawing.

105 The member of the car door closure to which our invention more particularly relates includes the destructible closure mem-

- ber 1, which is preferably formed of a thin and somewhat brittle board of suitable width,—say between four and twelve inches wide and preferably about eight inches, though this may vary somewhat. The ends of this board are nailed lightly to the posts at the sides of the door opening, on the inside of the car. Above this are nailed the door sections A, B and C, of ordinary construction, in the customary manner. In the present instance we have shown but three sections though four are frequently used, and sometimes five, and it will be understood that our invention is equally applicable to any number which it is possible to use. To the board 1 is secured an upright bar 2, of such material and dimensions as to possess considerable strength and stiffness. The bar may be secured to the board, as shown, by a bolt 3 engaged by a nut on the inside of the closure and provided with a wide washer affording a substantial bearing. Secured to the lower end of the bar is a strip of metal 4 which in applying the closure is carried inside the car and nailed to the car floor. A U-shaped staple 4^a, rounded between its prongs, is preferably employed as the fastening means for securing the strip 4 to the bar, to provide for its ready detachment. The strip may consist of a piece of box strapping of suitable weight (say about 18 gauge), though wire may be employed if desired. Towards the upper end of the post, opposite the joint between the upper two door sections, a strip of metal 5, which may be formed of the same material as the strip 4, is secured to the bar, and in applying the closure the free ends of this strip are twisted and carried inside the closure between the door sections, and preferably both ends bent upwardly and secured to the upper section, as shown in Figs. 1 and 2, or if desired, one end bent downwardly and nailed to the section B and the other upwardly and nailed to the section C, as shown in Figs. 4 and 5. If desired the member 5 may be formed of wire, though a flat piece of box strapping is more readily applied.
- When the grain is to be unloaded the strip 5 is cut or broken and the staple 4^a withdrawn by a suitable tool, and the bar 2 employed as a wrench bar to break away the center portion of the closure member. In this manner an opening is provided at the bottom of the closure through which the grain may flow, and as the grain is removed the upper, middle and lower sections are taken down in order.
- If desired, the bar 2 may later be provided with a new closure member 1 and new securing members 4 and 5 for further use. In case the floor of the box car does not have a metal protecting plate or strip at the bottom of the door such as indicated by

the reference numeral 6 in Figs. 2 and 3, the strip 4 may be dispensed with and a cleat 7, nailed to the floor, (see Fig. 8) be employed to resist outward pressure on the lower part of the bar 2.

In Figure 7 we have illustrated an alternative method of securing the upper end of the bar 2, consisting of an angular stiff metal bracket plate 9 fastened to the upper end of said bar and also firmly secured to the upper door section by nails or screws.

Our invention not only has the advantage of providing a ready means for effecting an opening for the grain at the level of the floor of the car, but also equalizes and distributes the strain on the door sections, and keeps them in vertical alignment. The lowermost section, it may be explained, does not sustain as great internal pressure as the middle one, since the lower stratum of grain rests on the car floor, and is not subject to true fluid pressure in a lateral direction. The upper stratum of grain, opposite the door section C, likewise sustains less pressure than the stratum opposite the section B, though, for the reason that the depth of the grain is less. The middle section (or sections, if more than three are employed) therefore sustains the greatest pressure, and obviously this is in part communicated by the bar to the upper and lower sections and the anchorage to the car floor. Ordinarily there will be a slight amount of slack in the bottom securing strip 4, so that part of the outward pressure of the grain will be sustained by the lower door section. This is of advantage in preventing undue strain on the middle section and an unequal deformation of the door sections, and in use they will retain their original shape much longer.

The provision of the destructible section 1 moreover increases the height of the closure by an amount equal to its width, and therefore increases the carrying capacity of the car to that extent.

We claim:

1. A car closure comprising horizontal door sections, a lower destructible closure member, and an exterior bar member, said bar member being secured to an upper door section and equipped at its lower end with a strap member anchored to the car floor inside said closure.

2. A car closure comprising horizontal door sections, a lower destructible closure member, and an exterior bar member, secured to said destructible member and anchored to the car floor, said bar being equipped near its upper end opposite a joint between the door sections with a strap passing between said sections and anchored to the upper section.

3. A car closure comprising horizontal door sections, a lower destructible closure

member, and an exterior bar member, secured to said destructible member and anchored to the car floor, said bar being equipped near its upper end opposite a joint 5 between the door sections with a strap having its two ends passed between said section and an end fastened to the upper section and the other end to the lower section.

4. A car closure comprising horizontal 10 door sections, a destructible closure member beneath said door sections and an exterior bar member secured to said destructible closure member and flexibly secured to the car floor and removably secured to an upper 15 door section, whereby the upper end of said bar may be released and the bar swung outward to pry the destructible member loose.

5. In a closure for grain car door openings, a lower member adapted to readily yield outwardly when unsupported intermediate its ends, a lever bar firmly secured to said member and adapted to extend upwardly therefrom, means for yieldingly securing the upper end of the lever against the 20 closure member, and means located on the floor of the opening preventing the direct outward movement of the lever but permit- 25

ting it to swing, whereby when the upper end of the lever is released it may be swung outward and draw with it said lower member of the door closure. 30

6. In a grain door of the class described, a yielding lower member, a bar secured to said member near the upper edge thereof, means flexibly securing the lower end of the 35 bar to the floor of the opening in the car, and means for releasably securing the upper end of the lever against the closure member.

7. In a grain car door closure, a lowermost member adapted to readily yield to an outward strain when unsupported intermediate its ends, a lever bar secured to said member adjacent its upper edge, a strap extending under said lower member and attached to the car floor within the opening 40 and flexibly connecting the lever to the car floor, and releasable means for holding the upper end of the lever in position, the construction being such that when the upper end of the lever is released and drawn outward said lower member swings outward 45 with the lever. 50
